UNITED STATES PATENT OFFICE.

CARL W. WEISS, OF NEW YORK, N. Y., ASSIGNOR OF ONE-HALF TO CHARLES KRUSE, OF SAME PLACE.

CASH INDICATING, RECORDING, AND REGISTERING MACHINE.

SPECIFICATION forming part of Letters Patent No. 447,036, dated February 24, 1891.

Application filed February 19, 1890. Serial No. 341,016. (No model.)

To all whom it may concern:

Be it known that I, CARL W. WEISS, of the city, county, and State of New York, have invented certain new and useful Improvements 5 in Cash Indicating, Recording, and Registering Machines; and I do hereby declare that the following is a full and exact description thereof, reference being had to the accompanying drawings, and to letters and figures 10 of reference marked thereon, making a part of this specification—

My invention relates to that class of machines for indicating, recording, and registering cash payments which are operated by a 15 crank, and has for its object to provide a simple, compact, efficient cash-machine at a low cost.

It consists in the combination and arrangement of the several mechanical devices, sub- 20 stantially as is hereinafter described and claimed.

In the accompanying drawings, Figure 1 is a rear view of the machine with its outer casing removed; Fig. 2, a transverse section 25 in line *xx* of Fig. 1 with certain portions thereof broken away to exhibit the underlying mechanism; Fig. 3, a detail illustrating the movement of the carrying-pawl by which the adding mechanism is actuated; Fig. 4, a 30 transverse section in line *yy* of Fig. 1, illustrating the movements of the printing mechanism; Fig. 5, a transverse section in line *zz* of Fig. 1, illustrating the double-acting pawl controlling the movement of the main crank- 35 shaft, and Figs. 6 and 7, detailed views, partly in section illustrating modifications of the invention.

Similar letters and numerals indicate like parts in all of the figures.

40 A represents the bed-plate, and B B' the vertical end plates of the machine firmly secured to said bed-plate.

C is a shaft extending parallel with the bed-plate and rotating in suitable bearings in the 45 two end plates B B'. An indicating disk or wheel D (see Figs. 1 and 2) is fixed upon one end of said shaft to revolve with it, preferably outside of the proximate end plate B. The figures representing the several denomina- 50 tions of the cash payments to be registered

and recorded are marked upon said indicating-wheel, preferably upon its rim, as shown in Figs. 2 and 4, and the wheel is incased so that but one denomination shall be brought to view at a time through a suitable sight-opening E E, formed in the casing on each side of the disk. A printing-wheel F, (see Figs. 1 and 4,) bearing type corresponding with the numbers upon the indicating-wheel D, is also fixed upon that end of the shaft C 55 which is proximate to the indicating-disk, and the train of numbering-wheels G G' G² G³ in the adding mechanism is mounted to revolve loosely upon the same shaft. The shaft C is turned to set the indicating and 60 printing wheels by means of a milled wheel C', fitted on the extremity of its opposite end outside of the end plate B'. (See Fig. 1.)

The units-wheel G in the train of adding-wheels is preferably placed next to the printing-wheel F. It is formed with a lateral ratchet-wheel W, having a concentric flange H projecting therefrom toward the printing-wheel F, the ratchet-wheel and its flange being made integral with said units-wheel or 70 made fast thereto, as shown in Fig. 1.

A wheel I, of a diameter exceeding that of the flange H, is mounted to revolve loosely on the shaft between the flange and the printing-wheel, and is geared by means of a toothed 80 wheel J (see Fig. 1) to a driving-pinion J', fixed on a lower shaft K, mounted parallel with the shaft C, to rotate in the end plates B B' of the machine, this shaft K being actuated by a crank K' on its outer end.

A pawl *a* is pivoted loosely to the side of the wheel I in a manner to overhang and drop into contact with the periphery of the flange H, and its contact is enforced by means of a spring *b*. (See Fig. 2.) The flange H serves 90 as a carriage for a series of clutch-pins *c c c*, corresponding in number with the figures on the indicating-wheel D and the printing-wheel F, said pins being inserted radially through openings in the periphery of the flange to 95 play longitudinally therein, their inner ends being supported by a second annular concentric flange H', (see Fig. 2,) secured to or formed integrally with the units-wheel G to encircle the axial shaft C at a short distance radially 100

therefrom. The outer end of each pin *c* terminates in a head, (see Fig. 2,) which prevents it from dropping inward, this head being so rounded off as to allow the pawl *a* to slide freely over it when the pin is carried inward into its normal position, with its head in contact with the peripheral surface of the annular flange or carriage *H*. When in this position the inner end of each pin *c* projects 10 slightly through the second annular flange *H'* toward the shaft *C*. The several pins *c c c* are automatically carried inwardly and held in their normal position by means of a spiral spring encircling each between the outer and 15 inner flanges *H H'*, as shown in Fig. 2.

A lug *d* is fitted (see Fig. 2) to project from the periphery of the shaft *C* in register with the inner ends of the clutch-pins *c c c*, so as to push them out as in the rotation of the 20 shaft it is in turn brought into contact with each. As these pins correspond severally with the numbers on the indicating-wheel *D*, secured to the shaft *C*, it follows that when the shaft is turned to bring any one of the 25 numbers on said wheel to the sight-openings *E* the lug *d* will force outward the corresponding clutch-pin *c*, so that the head of the pin will project beyond the periphery of the carriage *H* far enough to engage the pawl *a* 30 as it is carried around and over the face of said carriage, and when this engagement takes place the carriage will be made to revolve with the pawl *a* in unison with the wheel *I*, carrying said pawl.

35 The forward movement of the wheel *I* is positively arrested so soon as it has made a single revolution by means of an arm or 40 detent *L*, so pivoted upon the crank-shaft *K* as to admit of swinging into contact with the periphery of the carriage *H* in advance of the pawl *a* to stop it. This arm *L* is made 45 to revolve with the crank-shaft *K* by means of a spring-actuated friction-block *e*, (see Fig. 3,) playing against the shaft in a recess in the 50 collar *f*, from which the arm projects, the pressure of the block *e* being adjusted by means of a set-screw *g*, or, as an equivalent, by means of an adjustable elastic disk *e'*, made to bear against the end of the collar *f*,

55 as shown in Fig. 7. The movement of said arm *L* in unison with the shaft *K* is arrested before it comes into contact with the carriage *H* by means of a lateral projection *L'* on the arm *L*, (see Fig. 1,) which will bear against the 60 periphery of the wheel *I*. At the proper moment for arresting the movement of the carriage *H* a recess *M* (see Fig. 2) cut in the periphery of the wheel *I* permits a further movement of the arm *L* sufficient to bring it

65 into contact with the carriage and allow it to come into engagement with the projecting head of the one clutch-pin *c*, which, being engaged and held in its outer position by means of the pawl *a*, as shown in Fig. 3, is brought forward thereby against the end of the arm. The recess *M* is so formed as to be guarded by an overhanging peripheral pro-

jection *i*, which operates to prevent the arm *L* from entering the recess at the moment the wheel *I* begins its forward movement, it being essential that it shall not enter until the movement is completed. The rotation of the shaft *K* is arrested so soon as its actuating-crank *K'* has made a complete revolution in either direction by means of a stop *N*, projecting from the end plate *B'*. A reversal of its movement in either direction when once the movement has commenced is prevented by the engagement of a double-acting detent *O*, pivoted to the inner face of the end plate *B'*, with a denticulated wheel or ratch *P*, secured upon the shaft in proximity to said face. The inner end of this pivoted double-acting detent *O* is armed with two teeth *h h*, (see Fig. 5,) either of which may be brought 75 into engagement with the ratch *P* by an oscillation of the detent. Each tooth *h* is held in engagement with the ratch by means of an angular projection *q* upon the free end of a pivoted swinging latch *Q*, which is carried 80 by means of a spring *j* against the angular extremity of an arm *k*, extending rearwardly from the pivoted detent. The latch *Q*, by its automatic engagement with the end of the arm *k*, will hold it in position with one or 85 other of the teeth *h h* in engagement with the ratch *P*, while the beveled surfaces of the arm and latch will allow the double-acting detent *O* to be moved to change the engagement of its teeth with the ratch by causing 90 the latch to slip back when pressure is applied to the working end of the detent in the one direction or the other. Pressure is thus applied to the detent *O* to change its position 95 just before the crank *K'* reaches the stop *N* in its movement in either direction by means of a pin *l*, projecting from the side of the ratch-wheel *P* in position to strike an extension *m* of the detent, formed to overlap 100 the side of the wheel.

105 The wheel *I*, carrying the pawl *a*, is so adjusted with reference to the shaft *K*, to which it is geared, as that the recess *M* in the periphery of the wheel will be brought into position to allow the arm *L* to drop against the carriage *H* at the moment the forward movement of the shaft *K* is completed and its crank *K'* strikes the stop *N*. Upon the reverse movement of the shaft *K* the arm *L* will be thrown back from the carriage *H* until 115 it strikes a stop-post *N'*, made to project upward from the base *A* for the purpose. (See Figs. 1 and 2.)

120 The forward movement of the shaft *K* (see the arrow in Fig. 2) operates to carry the pawl *a* forward, and the position of the pawl is so adjusted as that it will carry the projecting clutch-pin *c*, which it engages, against the end of the arm *L* simultaneously with the contact of the crank *K'* with the stop *N*.

125 The position of the units figure on the indicating and printing wheels (represented as 5 in the drawings) is so adjusted as that when said figure is brought to sight and to the line 130

of print the clutch-pin *c* first removed from the normal resting-point of the pawl *a* will be forced outward by the push-pin or lug *d* on the indicating-shaft *C*, as illustrated in Fig. 2, so that when the pawl *a* in its forward movement engages said clutch-pin *c* it may carry the units-wheel *G* of the adding mechanism forward one step only, said movement operating in the customary manner to register 10 the one unit.

If the indicating-wheel be set for the second figure (10 in the drawings) to indicate two units, the second clutch-pin will be forced out to engage the pawl *a* as it moves forward, 15 so that the pawl in engaging and moving said second pin forward against the arm *L* will move the adding mechanism far enough to register two units, and so on, the distance of each clutch-pin from the normal resting-point 20 of the pawl *a* determining the degree of movement of the adding mechanism in correspondence with the value of the figure brought to sight and in line for print by the primary adjustment of the shaft *C*.

25 The ratchet *W* on the units-wheel *G* of the adding mechanism is engaged by a spring-actuated detent *G'*, pivoted on the shaft *K*, as shown in Figs. 1 and 2, and which operates in the customary manner to prevent a reverse 30 movement of said units-wheel.

The printing mechanism, by means whereof the payment indicated and registered may be recorded upon a strip of paper, consists of a movable platen *R*, projecting to overhang the 35 periphery of the type or printing wheel *F* from a plate *R'*, fitted to slide vertically against the inner face of the end plate *B* of the machine. This slide-plate or slide *R'* is steadied and guided by means of wide headed 40 studs *p*, projecting from the end plate through vertical slots in the slide, (see Figs. 2 and 4,) said slide being likewise slotted to permit of the passage of the shafts *C* and *K* through it. (See dotted lines in Fig. 4.)

45 The slide *R'* and its platen *R* are so adjusted as that the platen may drop into contact with the uppermost type on the wheel in manner to produce an impression of the type upon an interposed strip of paper, this movement being enforced by a spring *S*, attached to slide *R'* and bed-plate *A*. The platen is then lifted clear of the type to permit a rotation of the type-wheel by means of a cam *T*, projecting from the shaft *K* and engaging a 55 pin *T'* on the slide *R'*, as shown in Figs. 1 and 4.

The cam *T* is so adjusted as that when the crank *K'*, actuating the shaft *K*, is in its normal position at rest, as shown in Fig. 1, the 60 platen shall be in its elevated position, but will drop when the crank begins its forward movement. When the platen *R* is thus elevated, the shaft *C* is left free to rotate in either direction to permit an adjustment of 65 the indicating-wheel and the type-wheel; but it is locked so soon as the slide *R'* is, by the movement of the crank *K'*, permitted to drop,

and it will remain thus locked until the crank has been returned to its first or normal position and the slide thereby again elevated. 70 This locking of the shaft *C* is effected by means of a detent *U*, pivoted to swing freely on the shaft *K* in position to engage a toothed wheel *U'*, secured upon the shaft *C* adjacent to the printing-wheel, the release of the detent being positively prevented, while the slide *R'* is depressed by means of a lug *V* on said slide *R*, which moves into engagement with the end of an arm *U*, projecting from the detent, as illustrated in Fig. 4. 80

The automatic engagement of the detent *U* with the wheel *U'* is enforced by means of a spring *U*.

The type brought to line of print under the platen *R* are inked by means of an inking-roller *Y* upon the end of an arm *Y'*, mounted upon the shaft *K*, with freedom to turn loosely thereon, but which is made to move with the shaft by means of a spring-actuated friction-block *X*, fitted radially in the collar 90 from which the arm projects, so as to bear against the shaft, its pressure thereon being adjusted by a set-screw *X'*. By this means the inking-roller *Y* is made to swing away from the type at the first movement of the 95 shaft *K*, and when clear of the type its movement is arrested by a stop *t*, while the shaft *K* continues independently its forward movement to complete its revolution. So soon as the movement of the shaft *K* is reversed it 100 will carry back the roller *Y* from the stop *t* until the roller is arrested by contact with the platen *R*, and so soon as the platen is elevated it will carry the roller yet farther over the type and to its first position. 105

In the operation of the machine the amount of the cash payment to be recorded is first indicated by turning the shaft *C* by means of the milled head *C'*. The movement of the shaft *C*, carrying the indicating-wheel *D*, operates simultaneously to turn the printing-wheel *F*, so as to bring the type corresponding to the amount indicated to line of print and to force outward the clutch-pin *c* in the carriage *H* corresponding to said amount, so 110 that its head shall project in position to engage the pawl *a*. This being accomplished, the crank *K'* is turned from its normal position of rest at one side of the stop *N* until it strikes the opposite side, and is then returned 115 to its first position, thereby causing the shaft *K* to make a nearly complete revolution in one direction and back again. In the forward movement of the shaft *K* the pawl *a* upon the side of the wheel *I* will be carried 120 from its initial point of rest over the periphery of the carriage *H* and will glide freely over the heads of the clutch-pins *c c* until it reaches the one pin which has been forced outward, as described, by the adjustment of 125 the indicating-wheel. It will then by its engagement with said pin cause the carriage *H* (and the units-wheel *G*, to which the carriage *H* is attached) to partake of its movement, so 130

that the units-wheel will turn with it the remainder of the distance, which will be proportional to the value of the amount indicated, and will thus produce a registry of said amount by the adding mechanism. At the first move of the shaft K the arm L will be carried into contact with the periphery of the wheel I, and just as the shaft completes its forward movement the arm will by reason of the recess M cut in said periphery be permitted to drop into contact with the periphery of the carriage in advance of the outwardly-projecting clutch-pin, so as to provide, in effect, at the completion of its forward revolution a second stop for the shaft K and for the carriage and the units-wheel carried thereby. At the first movement of the shaft K upon its return-stroke the arm L is thrown back against the stop-post N' clear of the carriage II and of the wheel I. The reverse movement of the shaft operates to carry back the pawl a to its first position. In the meantime the shaft C and its connections are locked immovably and the printing mechanism actuated by the mediate operation of the slide R' in manner as described, while a reverse movement of the shaft K in either direction after the movement has begun and until it is fully completed is prevented by the automatic action of the double-acting pawl O in manner as described.

As a modification of my invention I contemplate constructing my machine with a sliding indicating-bar 10, as illustrated in Fig. 6 of the drawings. This bar is provided with a pointer 11 to slide over a series of figures upon an indicator-plate 12, representing the several values to be registered, and which are placed at regular intervals apart. A series of clutch-pins 14 14 14, corresponding in number to the figures on the indicator-plate 12, is fitted in the frame 13 of a carriage made to slide longitudinally over the indicating-bar 10. These clutch-pins 14, placed at regular intervals corresponding with the intervals between the figures on the indicator-plate, are left free to play vertically in the frame, and each is formed with an enlarged head to prevent it from dropping inward upon the slide 10, said head being so formed as not to prevent a suitable pawl from sliding freely over it. Each pin is also automatically held in its inward position by means of an encircling spring 15. The carriage 13 is mounted in suitable ways to slide longitudinally parallel with the indicating-bar 10, and is attached to a rack 18, which gears with the first wheel 19 in a suitable train of adding-wheels. A lug 16 is formed upon the indicating-bar 10 in such position as that when the pointer 11 is moved to one of the figures on the indicator 12 the lug will be carried under the particular clutch-pin which corresponds in its order or position with the figure indicated and will operate to push said pin up against the stress of its spring and cause its head to project up above the top bar 17 of the carriage.

Above this top bar 17 is fitted a registering-bar 20, adapted to slide freely longitudinally over it. The forward end of this registering-bar 20 is fitted with a spring-actuated pawl 21, adapted to drop and rest upon the top of the bar 17 in advance of the bar 20.

The reciprocating movements of the indicating-bar 10 and registering-bar 20 may be produced simply by the direct application of the hand of the operator thereto or in any other suitable manner known to the art. A reverse movement of the actuating-bar 20 in either direction, when once its movement has commenced, is prevented by the engagement of a double-acting pawl O', pivoted over the bar to engage a ratch p', formed thereon. This double-acting pawl is armed with two teeth h' h', either of which may be brought into engagement with the ratch p' by an oscillation of the pawl.

This device, which is a modification of the double-toothed pawl O, applied in manner as hereinbefore described as a double-acting 90 detent to control the movements of the main shaft K, is governed in like manner by a spring-actuated swinging latch Q', which, by its engagement with a projecting arm k' on the pawl, operates to retain it in either position to which it may be carried by the movement of the bar 20 as it completes its stroke in either direction, the pawl being tripped to change its position at the end of each stroke by means of the projections l' l' on the bar. 100

In the operation of the machine constructed in this form the amount of the cash payment to be registered is first noted by moving the bar 10 until the pointer 11 indicates the amount on the indicating-plate 12. This movement of the bar 10 will operate to force up the particular clutch-pin 14 which corresponds to said amount. Then by pushing the registering-bar 20 forward its pawl 21 will engage the head of the uplifted clutch-pin 110 and thereby produce a movement of the carriage 13 in unison with the bar 20 for the remainder of its stroke, and the movement of the carriage 13 will actuate the adding mechanism, the extent of said movement being 115 proportionate to that of the carriage and determined by the position of the particular clutch-pin which may be uplifted to engage the pawl 21. If the last pin in the series be thus uplifted, the unit will be registered; if the first, the frame will be moved to its full 120 limit and the highest amount will thereby be registered.

The automatic return of the carriage 13 and registering-bar 20 is produced by means of a 125 spring 22 so soon as the forward stroke of the bar is completed.

I claim as my invention—

1. The combination, in a cash-registering machine, of an indicating device to exhibit 130 the amount of each cash payment, an adding mechanism, a carriage geared to the adding mechanism to actuate the same by its movement in one direction, a reciprocating pawl

traveling in a path parallel with the carriage, a device for moving said pawl independently of the carriage, a series of clutch-pins corresponding in number with the figures on the indicating device and which are mounted to play in the carriage, and an indicating device moving said pins severally in correspondence with the amount exhibited by said device into position for engagement by the pawl in its movement, whereby the carriage and the adding mechanism geared thereto are actuated by the pawl, substantially in the manner and for the purpose herein set forth.

2. The combination, in an indicating and registering machine, of an indicating mechanism and indicator and operating device therefor, one or more registering-wheels, a reciprocating driving mechanism therefor, a series of interposed clutch-pins numbered to correspond with the indicator and severally moved by the operation of the indicating mechanism each into position to couple the driving and registering mechanism at a point corresponding with the figure indicated, and thereby determine the movement of the registering-wheels, and disengaging mechanism to uncouple the same at the end of each forward stroke of the driving mechanism, substantially in the manner and for the purpose herein set forth.

3. The combination, with the driving mechanism, the indicator, the indicating mechanism, and the adding mechanism in a cash-registering machine, of a series of clutches, as *c c*, moving in unison with and connected to the adding mechanism as a means for actuating the same and severally adapted to be engaged by an independent driving mechanism, and a device, as *d*, actuated by the indicating mechanism to move severally and independently and to hold each clutch in correspondence with a like position of the indicator and in position to be engaged by the driving mechanism, substantially in the manner and for the purpose herein set forth.

4. The combination, in an indicating and registering mechanism, of an indicating mechanism and movable indicator, an operating-wheel therefor, one or more registering-wheels and a reciprocating driving-wheel mounted loosely on the same spindle with the indicator, a series of radial clutch-pins mounted to revolve loosely about said spindle in proximity to the driving-wheel and numbered to correspond with the indicator, a fixed lug on the spindle adapted to move the clutch-pins severally into operative position each in correspondence with the figure indicated, a coupling device on the driving-wheel to engage the operative clutch-pin as the driving-wheel moves forward, and disengaging mechanism to release it at the end of said movement, substantially in the manner and for the purpose herein set forth.

5. The combination, in a cash indicating and registering machine, of a rotating shaft, an indicating device actuated thereby, an

adding mechanism including a wheel mounted to revolve loosely upon said shaft, an annular concentric flange or carriage revolving with said wheel, a series of clutch-pins corresponding with the figures on the indicating device and mounted to play radially through the periphery of said carriage, a lug upon the shaft made to register with said clutch-pins and to carry them severally outward when brought into engagement therewith, a reciprocating pawl mounted to revolve about the shaft on which the indicator is mounted, a crank-shaft mounted parallel with said indicator-shaft and geared to said pawl to produce its revolution, and a stop limiting the rotation of the crank-shaft to a single revolution in either direction, substantially in the manner and for the purpose herein set forth.

6. The combination, in a cash indicating and registering machine, of a rotating shaft, an indicating device actuated thereby, an adding mechanism including a wheel mounted to revolve loosely upon said shaft, an annular concentric flange or carriage revolving with said wheel, a series of clutch-pins corresponding with the figures on the indicating device and mounted to play radially through the periphery of said carriage, springs retracting said clutch-pins, a lug upon the shaft made to register with and engage said clutch-pins, a wheel mounted to revolve loosely upon the shaft adjacent to the carriage and having a re-entrant recess in its periphery, a pawl pivoted to the side of said wheel to overhang and rest upon the carriage and glide over its periphery, a crank-shaft mounted parallel with the shaft upon which the indicator is mounted and geared to the wheel on which the pawl is mounted, an arm pivoted on said crank-shaft with a frictional bearing thereon and carried thereby against the periphery of the wheel carrying the pawl and into contact with the face of the carriage, and a stop to arrest said arm when it swings outward, substantially in the manner and for the purpose herein set forth.

7. The combination, substantially as and for the purpose herein set forth, of a rotating shaft, as *K*, an arm pivoted upon said shaft to swing loosely thereon, as *L*, a friction device, as *e*, interposed between the arm and shaft, and an extraneous stop, whereby the arm partakes of the movement of the shaft in either direction until arrested by an extraneous stop without preventing by its arrest the continued movement of the shaft independently thereof.

8. The combination of the rotating shaft carrying the indicating mechanism, the wheel in an adding mechanism revolving loosely upon said shaft, the parallel crank-shaft, the stop, the arm pivoted loosely upon said crank-shaft to swing in one direction into engagement with said wheel and in the other with the stop, and the friction device interposed between the arm and its pivotal shaft, whereby the arm will partake of the movements of

the shaft until brought into engagement with the wheel or stop and the shaft be allowed to continue its movement independently thereof, substantially in the manner and for 5 the purpose herein set forth.

9. The combination, with the indicating device and the rotating shaft actuating the same, in a cash registering and recording machine, and with a type-wheel fixed to said 10 shaft, of a parallel reciprocating crank-shaft, a stop therefor, a spring-actuated slide mounted vertically adjacent to the type-wheel, a platen carried by said slide into contact with the type-wheel, a cam on the crank-shaft actuating 15 the slide to lift the platen from the type-wheel when the crank is in its first or normal position, a toothed wheel fixed to the shaft, a dog pivoted to the shaft to swing into engagement with said toothed wheel, and a 20 lug on the slide engaging the dog, whereby the dog is locked and a movement of the indicating-shaft prevented when the crank is moved from its first position, substantially in the manner and for the purpose herein set 25 forth.

10. The combination, in a cash indicating, recording, and registering machine, of a rotating shaft, a type or printing wheel fixed thereon, an indicating device actuated thereby, a loose wheel upon said shaft, adding 30

mechanism geared thereto, an annular concentric flange or carriage revolving therewith, a series of clutch-pins corresponding with the figures on the indicating device and mounted to play radially through the periphery of said 35 carriage, springs retracting said clutch-pins, a lug upon the shaft made to register with said clutch-pins and to carry them severally outward when brought into engagement therewith, a reciprocating pawl mounted to revolve 40 about the indicating-shaft, a crank-shaft mounted parallel with the indicating-shaft and geared to said pawl to produce its revolution, a stop limiting the rotation of the crank-shaft to a single revolution in either 45 direction, a vertical spring-actuated slide mounted adjacent to the printing-wheel, a platen carried automatically by said slide into contact with the type-wheel, and a cam upon the crank-shaft engaging the slide to 50 lift the platen from the type, substantially in the manner and for the purpose herein set forth.

In testimony whereof I have signed my name to this specification in the presence of 55 two subscribing witnesses.
